DESIGN FOR A LACE CURTAIN.

44,879.

Specification for Design.

Patented Nov. 11, 1913.

Application filed September 6, 1913. Serial No. 788,480. Term of patent 7 years.

To all whom it may concern:

Be it known that I, JAMES WATERFIELD, a citizen of the United States, residing in the city of Philadelphia, State of Pennsylvania, have invented a certain new, original, and ornamental Design for a Lace Curtain, of which the following is a specification, reference being had to the accompanying drawing, forming part thereof.

The figure is a plan view of a portion

of a lace curtain, of which the ornamental border is the novel and characteristic feature, showing my new design.

I claim:—

The ornamental design for a lace curtain, as shown.

JAMES WATERFIELD.
